UNITED STATES PATENT OFFICE

JAMES T. BROWN, OF JAMAICA, NEW YORK, ASSIGNOR TO BOND ELECTRIC CORPORATION, OF NEW YORK, N. Y., A CORPORATION OF DELAWARE

FLASHLIGHT

Application filed April 4, 1928. Serial No. 267,195.

This invention relates to flashlights and more particularly to the assembly of the component parts thereof.

In some flashlights the lamp socket supporting end has been positioned upon the end of the battery casing by a hood collar to which the lens and reflector are adapted to be removably secured and the lamp socket supporting end has been permanently retained in position by means of an expandable metallic ring soldered in place within the hood collar.

A primary object of the present invention is the construction and arrangement of such component elements of a flashlight whereby the lamp socket supporting end may be permanently and securely mounted in position by the performance of a minimum number of operations. To this end the expandable ring and the consequent soldering operation are done away with and the hood collar is so constructed as to retain the lamp socket supporting end permanently in operative position.

More particularly, in accordance with the invention, the lamp socket supporting end is secured on the end of the battery casing by means of a spacing member or insulating annulus of a shape substantially that of the flashlight casing, which spacing member is retained in place by an inturned flange formed on the threaded hood collar.

In order that the invention may be clearly understood the same will now be described in greater particularity in connection with the accompanying drawings illustrating one modification by which the invention may be realized, and in which:

Figure 1 is a longitudinal sectional view of the forward end of a flashlight showing the component parts in assembled relation.

Figure 2 is an end view of the flashlight with the lens, reflector and hood removed and showing the lamp socket supporting end, parts being broken away in the interest of clearness.

Figure 3 is an exploded view, in perspective, showing the component elements of the forward end of the flashlight in their order of assembly.

In the illustrated embodiment the flashlight casing or container for the batteries

(not shown) is indicated at 10 and is preferably in the form of a cylindrical tube and may be of an insulating material, such as fibre. Resting upon the upper edge of this battery casing 10 is a disc like end 11 supporting the lamp socket 12 and of a diameter substantially that of the outside diameter of casing 10. The lamp socket 12 passes through the centrally disposed aperture 13 in the disc 11 and through the centrally disposed aperture in a metallic disc 14 with which it makes electrical contact. The metallic disc 14 is connected to the end of a conductor 15, preferably in the form of a ribbon, leading to the switch (not shown) on the battery container 10. The metallic disc 14 is secured to the insulating disc 11 conveniently by diametrically disposed eyelets 16 and one of these eyelets may also serve to secure the conductor 15 in the electrical connection with the metallic disc 14. Insulated from the metallic disc 14, say by a disc 17 of fibre or other insulating material, is the central contact 18, which contact is adapted to make electrical connection with the positive pole of the flashlight battery and is exposed for connection with the terminal of the lamp not shown through the apertures in the insulating end disc 11 and metallic disc 14. The contact 18 is conveniently secured to the end disc 11 by the eyelets 19 which may for the sake of convenience in manufacture and to strengthen the disc assembly, pass through all of the parts, to wit, end disc 11 and fibre disc 17, the metallic disc 14 being formed with passages therefor large enough so that no electrical contact is made therewith.

To properly position the lens and reflector with respect to the flashlight lamp carried by the end 11, the hood collar 20 extends a material distance above the end 11 in order that its threaded portion 21 may receive the threaded end of the hood by which the reflector and lens are retained. To retain the end 11 in position therefore, in a manner which permits of convenient assembly with a minimum of operations and with the avoidance of the use of positive securing means such as solder, rivets or the like, an insulating spac-

ing member 22 of cylindrical form and of interior and exterior diameters substantially the same as the battery casing 10 is adapted to be positioned upon the end disc 11 and retained thereagainst by an inwardly directed flange 23 formed on the hood collar 20.

To assemble the forward end elements of the flashlight, therefore, it is merely necessary to set the end disc 11, carrying the contacts and lamp sockets, upon the end of the flashlight casing 10; place the cylindrical spacing member 22 thereupon and telescope the hood collar 20 over the assembled parts 10, 11 and 22 until the flange 23 rests upon the outer end of the spacing member 22. To secure the parts together thereafter it is only necessary to secure the hood collar to the battery casing 10 which may be accomplished by means, say, of one or more eyelets 24 or by staking the hood collar to the casing 10.

It will thus be seen that the flashlight end is permanently and securely mounted upon the end of the battery container so that the hood and its associated parts are carried at the proper position with respect to the lamp by operations of assembly of extreme simplicity requiring only fastening operations of a simple nature.

Various modifications will occur to those skilled in the art in the configuration and composition of the component elements going to make up the flashlight end structure as well as in the devices used to secure the hood collar to the battery casing without departing from the spirit and scope of the invention as set forth in the appended claim.

What I claim is:—

In a flashlight, in combination, a cylindrical battery containing a casing of non-conductive material, a lamp socket support comprising a disc of non-conductive material seated upon the end of the casing and of a diameter substantially that of the casing, a cylindrical member of non-conductive material of substantially the same outside diameter as the outside diameter of the casing and seated upon said lamp socket support disc, a hood collar telescoped over said end of the casing and formed with an inwardly extending flange at its outer end to engage the end of the cylindrical member remote from the lamp socket support disc, and means to permanently secure the hood collar to the casing to retain the parts rigidly together.

In testimony whereof I affix my signature.

JAMES T. BROWN.
